(57) **CLAIM**

The ornamental design for a brushroll for a floor cleaner, as shown and described.

DESCRIPTION

FIG. 1 is a left perspective view of a brushroll for a floor cleaner showing my new design;

FIG. 2 is a right perspective view thereof;

FIG. 3 is a front view thereof;

FIG. 4 is a rear view thereof;

FIG. 5 is an enlarged left side view thereof;

FIG. 6 is an enlarged right side view thereof;

FIG. 7 is a top view thereof; and,

FIG. 8 is a bottom view thereof.

The details of the brushroll for a floor cleaner shown in broken lines form no part of the claimed design.

1 Claim, 5 Drawing Sheets
